UNITED STATES PATENT OFFICE.

WILLIAM EDWARD PETCHUCK, OF MAHANOY CITY, PENNSYLVANIA.

VEGETABLE SLICER AND GRATER.

Specification of Letters Patent.

Patented Feb. 13, 1912.

1,017,586.

Application filed May 7, 1910. Serial No. 559,951.

To all whom it may concern:

Be it known that I, WILLIAM E. PETCHUCK, a citizen of the United States, residing at Mahanoy City, in the county of Schuylkill and State of Pennsylvania, have invented new and useful Improvements in Vegetable Slicers and Graters, of which the following is a specification.

The present invention provides a machine for household use whereby in the preparation of food the same may be grated or sliced, the machine embodying interchangeable cutting disks, whereby it may be readily adapted for grating or slicing.

15 The invention has for its object to provide a machine of the character aforesaid which will admit of access being readily had to the parts both for cleaning, inspection and substitution of the cutting disks when required.

20 A further purpose of the invention is to supply a machine for the purposes stated which may be cheaply manufactured and which in operation is effective and capable of being easily manipulated and not liable 25 to get out of order.

The invention consists of the novel features, details of construction and combination of parts, which hereinafter will be more particularly set forth, illustrated in the accompanying drawings, and pointed out in 30 the appended claim.

Referring to the drawings, forming a part of the application, Figure 1 is a perspective view of a vegetable grater and slicer embodying the invention. Fig. 2 is a perspective view of the machine having the upper part thrown open and the cutting disk removed. Fig. 3 is a vertical central section, the standard and gearing being in full lines. 35 Fig. 4 is a top view, showing a grater disk. Fig. 5 is a top view of a slicing disk.

Corresponding and like parts are referred to in the following description, and indicated in all the views of the drawings, by 45 the same reference characters.

The machine embodies a standard 1 having a clamp 2 at its lower end whereby the machine may be firmly attached to a table, shelf or other support. The upper portion 50 of the standard is offset and the lower part receives the drive gearing. The framework is mounted upon the standard 1 and is stayed by braces 3. The framework comprises a base 4 and a cover 5. The base 4 55 consists of a circular plate having a vertical flange 6. A portion is cut from the base

at one side of a diametrical line to form an opening 7 through which the material is discharged when the machine is in operation. A chute 8 inclines outwardly and downwardly from the base and is connected thereto upon the inner side of the discharge opening 7. The purpose of the chute 8 is to direct the cuttings away from the standard 1 and the operating gearing and into a bowl 60 or other receptacle placed upon the table, shelf or the like in convenient position to receive the cuttings.

A vertical shaft 9 is journaled at its upper end in the base 4 and at its lower end 70 in a portion of the clamp 2. The vertical shaft 9 is supported intermediate of its upper and lower ends by entering a recess formed in the lower part of the offset portion of the standard. A pinion 10 secured 75 to the lower end of the shaft 9 meshes with a gear wheel 11 fastened to the inner end of a shaft 12, which latter is mounted in the standard 1 and in a bracket 13 secured to a side of the standard, said shaft having a 80 crank 14 at its outer end for convenience of operation. The cutting disks 15 are adapted to be secured to the upper end of the vertical shaft 9. The cutting disks 15 are of a like size and may be of any formation according to the required cuttings. As shown 85 in Fig. 4 one of the cutting disks is provided with slicing knives and the other cutting disk is supplied with points for grating the material. Each of the cutting disks 90 is provided at its central point with an angular opening to receive a corresponding part at the upper end of the shaft 9, thereby preventing relative turning of the shaft and disk. The cutting disk may be secured to the 95 shaft in any manner, as by means of set nuts 16.

The upper part 5 of the framework comprises a hopper 17 and a shallow housing 18, which latter covers that part of the cutting 100 disk located immediately above the base at one side of the opening 7. The hopper 17 is located above the opening 7 of the base 4 and is adapted to receive the vegetables or other material to be grated, sliced, or cut in 105 any other manner. The upper part 5 is hinged to the base 4 opposite the opening 7 so as to be thrown to one side to be out of the way, as indicated in Fig. 2.

A follower 20 fits within the hopper 17 110 and enables pressure to be exerted upon the material placed therein to be cut. The fol-

lower has an outer flange 21 at its upper end to extend over the hopper 17 and limit the downward movement of the follower so as to prevent its coming in contact with the 5 cutting disk and injuring the same or dulling either the cutting blades or points.

The hopper 17 is provided with an internal transverse partition 22 which extends across the plate 4 and serves to limit the 10 movement of vegetable matter over the cutting disk 15 so that the material will pass directly from the hopper through the opening 7 and on to the chute 8. The flange 19 of the hopper forms a bearing for the cutting disk. The cutting disk and base or box 4 is so arranged that very little of the vegetable matter can contact with the shaft and thereby come in touch with the shaft which will be on the shaft to lubricate the same.

20 From the foregoing description, taken in connection with the accompanying drawings, the advantages of the construction and of the method of operation will be readily ap-

parent to those skilled in the art to which the invention appertains.

Having thus described the invention what is claimed as new, is:—

In combination, a standard, a base having an upstanding edge flanged and a delivery opening, a chute depending from said opening, a cover hinged and provided with a transversely extending member adapted to limit the movement of the material to be cut over said base, a material chamber formed in said cover and located above the delivery opening, a shaft extending through the base, a horizontal flange on the cover, and a cutter secured to the shaft and movable against the horizontal flange and under the material chamber.

40 In testimony whereof I affix my signature in presence of two witnesses.

WILLIAM EDWARD PETCHUCK.

Witnesses:

RICHARD CORBRIDGE,
JOE PETCHUCK.
